J. N. NEWSOM.
RIVET SETTING DEVICE.
APPLICATION FILED OCT. 1, 1915.

1,230,082.

Patented June 12, 1917.

INVENTOR.
Joseph N. Newsom

UNITED STATES PATENT OFFICE.

JOSEPH N. NEWSOM, OF ST. LOUIS, MISSOURI, ASSIGNOR, BY DIRECT AND MESNE ASSIGNMENTS, OF ONE-HALF TO C. E. ANDREWS, OF ST. LOUIS, MISSOURI, AND ONE-HALF TO HOLLIS CHRISTOPHER, OF DECATUR, ILLINOIS.

RIVET-SETTING DEVICE.

1,230,082.

Specification of Letters Patent. Patented June 12, 1917.

Application filed October 1, 1915. Serial No. 53,495.

To all whom it may concern:

Be it known that I, JOSEPH N. NEWSOM, a citizen of the United States, residing at St. Louis, Missouri, have invented a certain new and useful Improvement in Rivet-Setting Devices, of which the following is a full, clear, and exact description, such as will enable others skilled in the art to which it appertains to make and use the same, reference being had to the accompanying drawings, forming part of this specification.

My invention relates to new and useful improvements in rivet setting devices, the principal object of my invention being to provide a comparatively simple apparatus which includes a punch or awl and an anvil and which apparatus can be advantageously employed for setting or inserting rivets through two or more layers of material.

My improved device is particularly intended for use in setting rivets which are utilized for attaching two or more parts of the casing utilized in connection with pneumatic tires, it being understood that it is the present practice to utilize two old casings in the formation of what is known to the trade as a "remade" casing.

With the foregoing and other objects in view, my invention consists in certain novel features of construction and arrangement of parts, hereinafter more fully described, claimed and illustrated in the accompanying drawings, in which—

Figure 1 is a side elevational view of the awl or punch forming a part of my improved device.

Fig. 2 is a sectional view of the shank of the punch or awl and showing the removable point carried thereby.

Fig. 3 is a perspective view of the anvil forming a part of my improved device.

Fig. 4 is an elevational view of the anvil secured to a suitable support and with the tire casing positioned on said anvil.

Fig. 5 is a detail sectional view showing the application of a rivet to the work.

Fig. 6 is a detail sectional view showing the rivet in the work and with the washer applied to said rivet.

The awl or punch forming a part of my invention comprises a handle 10, preferably formed of metal and projecting from one end thereof is a shank 11, in the lower end of which is formed an aperture 12. Remov-

ably positioned in this aperture is a short shank 13 which is formed integral with a pointed head 14.

The anvil portion of the device comprises a base plate 15 which is adapted to be fixed to a suitable support such as a table 16 and projecting upwardly and outwardly from one side of said base plate is a bracket 17. Formed integral with the upper end of this bracket is a curved plate 18 which performs the functions of an anvil and a support for the work while the rivet is being positioned therein, and formed through said plate near one edge thereof is an aperture 19.

In the use of my improved device, the work through which the rivet is to be set is positioned on the anvil 18 with the point where the rivet is to be positioned directly over aperture 19. The pointed head 14 of the awl or punch is now inserted through the work and through the aperture 19 as shown by dotted lines in Fig. 4, after which the operator removes the pointed head 14 and its shank 13 from the lower end of said punch and which lower end projects beneath the anvil.

The shank of a rivet *a* is now inserted in the aperture 12 and the punch is drawn upward and disengaged from the work, thereby leaving the shank of said rivet in the aperture formed by said punch with the head of said rivet bearing against the underside of the work. Said work is now shifted sidewise a slight distance upon the anvil or until the head bears on the flat surface thereof, after which a washer is applied to the projecting end of the rivet shank and said projecting end is now hammered down in the usual manner to secure said rivet in position and firmly unite the material through which it is inserted.

A device of my improved construction is comparatively simple, can be easily and cheaply manufactured, and provides means for easily and quickly inserting rivets through one or more layers of material such as leather, rubber, fabric, or the like.

It will be readily understood that minor changes in the size, form and construction of the various parts of my improved device can be made and substituted for those herein shown and described, without departing from the spirit of my invention, the scope of which is set forth in the appended claim.

I claim:

In a device of the class described, the combination with, a work support and anvil comprising a base plate, a bracket projecting upwardly and outwardly from one side of said plate, and a curved plate integral with the upper end of said bracket, there being an aperture formed through said curved plate near one edge thereof, of a punch comprising a handle, a tubular member projecting from one end thereof, a stem

removably seated in the end of said tubular member and a pointed head carried by said stem, the largest diameter of which head is equal to the diameter of the tubular member. 15

In testimony whereof I hereunto affix my signature, in the presence of two witnesses, this 21st day of September, 1915.

JOSEPH N. NEWSOM.

Witnesses:

C. E. ANDREWS,
L. W. NEWSOM.
